UNITED STATES PATENT OFFICE.

HARRY P. MEIN, OF FLUSHING, NEW YORK.

BRASSIÈRE.

1,255,768.

Specification of Letters Patent.

Patented Feb. 5, 1918.

Application filed April 2, 1917. Serial No. 159,282.

To all whom it may concern:

Be it known that I, HARRY P. MEIN, a citizen of the United States, residing in Maspeth, Flushing, county of Queens, State of New York, have invented certain new and useful Improvements in Brassières, of which the following is a description.

My invention relates to improvements in brassières, wherein a snug fit is a prime requisite, and has among its objects to provide a garment which may be fastened across the back without leaving any bulging or protruding parts, and which, therefore, will not interfere with any design of evening gown which may be chosen; and has as a further and important object that it may be capable of practically a universal fit, to such an extent at least that for commercial handling it may be made in but few sizes to accommodate a variety of customers.

My invention also contemplates certain other minor novel details of construction, as hereinafter will be pointed out and claimed more definitely, reference being had 25 to the accompanying drawing, in which:—

Figure 1 is a perspective view of my improved device.

Fig. 2 is a rear elevation of the same shown open.

Fig. 3 is a sectional view, taken on the line III—III of Fig. 2.

Fig. 4 is a sectional view, taken on the line IV—IV of Fig. 3.

Fig. 5 is a detail view of a stiffening plate employed, the same being shown in its unbent form.

Similar numerals of reference denote corresponding parts in the several views.

The brassière consists essentially of a front section 1, which may be of any suitable material, and is shown provided with a central vertical line of ornamental fabric 2, and at its bottom with a tab 3, carrying the usual hook 4 for attachment to the corset of the wearer to retain the device in its adjusted position. Attached to the front section 1 at its side edges are two rear sections 5, 6, there being provided at the juncture of these sections with the front section 1 whalebone or other suitable stiffening elements 7 to maintain the shape of the garment at the sides, while extending in loop form from the top of said front section 1 at each side of its center to the top of the rear sections 5 and 6 are the shoulder loops 55 8, of silk or other suitable material. The rear section 5 is extended and terminates in substantially a point, to which is attached a tape 9 of some length. The other rear section 6 is also extended into substantially 60 point form, and has a similar tape 10 attached to its end, which is adapted to be tied with the tape 9 at the front to retain the garment in position. In order that said rear sections 5, 6 may cross each other, the 65 section 6 is provided with a vertical opening through which is passed the tape 9 of the rear section 5, and a portion of said section is drawn therethrough, as shown in Fig. 1, leaving a smooth unbroken back surface. More specifically, the construction of the aperture in the rear section 6 is shown 70 in Figs. 3 and 4, and consists of a rear whalebone stiffener 11 that lies against the outer surface of the rear section 6 at the 75 point where it is slotted vertically, and is covered on both sides by strips of fabric 12, one of said strips lying upon each side of the rear section 6 and being sewed to each other and the said section by lines of stitching 80 to retain the whalebone 11 in position. At the opposite side of the slit I provide a metal stiffener 13 having on one side a central pointed portion 14 and on the other side a wider projecting tab 15, said pointed 85 portion 14 and tab 15 being adapted to be bent to the configuration shown in Fig. 3, the point 14 passing through the rear section 6 and being bent back to clamp beneath the same. Also inclosed by said metal 90 stiffener 13 is a strip of whalebone 16, which is retained by stitching in suitable fabric 17 and overlies that portion of the rear section 6 which is inclosed in said metal stiffener. The metal stiffener 13, whalebone 95 16, and fabric 17 are connected to each other and to the rear section 6 by rivets 18 fastened through holes 19 in the ends of the metal stiffener 13 and finally uniting all of said parts, as best seen in Fig. 4. 100 Overlying the metal stiffener and its parts as a whole is a strip of ornamental fabric 18' sewed at one edge to the outside of the rear section 6, as best seen in Figs. 3 and 4, while a strip of fabric 20 is disposed over 105 said parts on the inside of the article, the same being fastened at its ends by the binding 21.

In operation, it will be apparent that when it is desired to position the article upon the body of the wearer, while the metal stiffener 13 will yield but slightly, the whalebone stiffener 11 upon the opposite side of the vertical slot in the rear section 6 may be sprung away from the metal stiffener so that the insertion of the tape 9 of the rear section 5 therebetween readily may be accomplished, and the tapered end of said rear section 5 may be drawn through to substantially the position shown in Fig. 1, in which position the tapes 9 may be brought around to the front and tied.

15 While I prefer to provide a filler in the shape of a whalebone strip 16 for the folded metal stiffener 13, the same is not essential, and may be omitted if desired.

It will be understood, further, that said construction presents an element at this point which will prevent any sagging of the device at the rear, and will tend to maintain it as a whole in a satisfactorily adjusted position.

25 Having thus described my invention, what I claim as new and desire to secure by Letters Patent, is:—

1. A brassière, comprising a rear portion slitted vertically to provide a slot for the

reception of the other rear portion, and 30 stiffening plates fixed at each side of said slitted portion and overlying one another.

2. A brassière, comprising a rear portion slitted vertically to provide a slot for the reception of the other rear portion, and 35 stiffening elements fixed at each side of said slitted portion and in register with one another, one of said stiffening elements consisting of a plate and the other element consisting of a whalebone stiffener, said plate 40 and whalebone being united at their ends.

3. A brassière, comprising a rear portion slitted vertically to provide a slot for the reception of the other rear portion, stiffening elements fixed at each side of said 45 slitted portion and in register with one another, one of said stiffening elements consisting of a metal plate having a pointed portion on one side and a tab on the other side, said pointed portion and tab being 50 bent to form a closure, the other element consisting of a whalebone stiffener, said plate and whalebone being united at their ends, and suitable fabric inclosing said stiffener.

In testimony whereof I hereunto set my hand this 31st day of March, 1917.

HARRY P. MEIN.
